UNITED STATES PATENT OFFICE.

LÉON CORDIER PINEL, OF PARIS, FRANCE.

APPARATUS FOR AUTOMATICALLY EXTINGUISHING CANDLES.

SPECIFICATION forming part of Letters Patent No. 312,291, dated February 17, 1885.

Application filed June 4, 1884. (No model.) Patented in France February 21, 1884, No. 160,479.

To all whom it may concern:

Be it known that I, LÉON CORDIER PINEL, a citizen of France, residing in the city of Paris, in the Republic of France, have invented 5 a new and useful Improvement in Apparatus for Automatically Extinguishing Candles, of which the following is a specification.

The object of this invention is to extinguish candles automatically, so that any one can go 10 to bed and leave the candle to be put out safely by the apparatus.

In the accompanying drawings, Figures 1 and 3 are face views of the apparatus. Fig. 2 is a side view; Fig. 4, a top view of the same. 15 Fig. 5 is a face view of the same, showing it combined with a shade-holder.

The apparatus is made of iron, steel, or brass wire. The lower portion is in form of a ring, *a*, which is passed over the candle *b* and 20 branches out at the sides *c c'*, which with the parts *d d'* forms a kind of elastic triangle. At the upper part the spring sides *c c'* are bent horizontally at *f f'*, so as to rest against the candle, as shown. (Figs. 1, 2, and 4.) These 25 horizontal parts *f f'* form the extinguishers, and may, if desired, also carry flat metal plates or enlargements *p p'*, which are soldered or otherwise secured to them. These parts *f f'* are bent back at *g g'* in form of ears which 30 terminate in the loops *h h'* of any form.

The action of the apparatus is as follows: Having placed the ring *a* over the candle *b*, the 35 spring sides *c c'* are opened by drawing them apart by aid of the rings *h h'*. The nipping parts *f f'* are then pressed down as low as required on the candle, or as low as it is intended the candle shall burn before being extinguished, and the position the parts *f f'* occupy will be the 40 point of extinction of the flame, as the tallow or wax being consumed offers no further support to the parts *f f'*, so that the said parts *f f'* or their enlargements *p p'* nip the wick between them and put out the light without any smoke and prevent the fat from running over. Fig. 45 3 shows the candle extinguished by this means. The enlargements *p p'* may be sufficiently large to prevent the wick smoking. If the candle burns more on one side than the other, then

on the side that is burned away the spring or side *c* or *c'*, as the case may be, alone advances 50 the part *f* or *f'* to the wick; but the ears *g* or *g'* (on whichever side of the candle is burned away) come into play and rest against the candle, and so check the further advance of the extinguishing part *f* or *f'*. In this manner 55 the said part *f* or *f'* remains till the other side of the candle burns level, when the other plate meets it and the candle is extinguished. The two parts *t t'*, which are suspended from the ears *g g'*, may serve to hang a watch, *m*, upon 60 by aid of the hook *i*. (See Fig. 5.)

To the rings *h h'* may be fixed the supports *s s'* of a shade, *A*, Fig. 5. The wire forming the support to the shade may be of a piece 65 with that forming the extinguisher.

I claim nothing that is shown in German Patent No. 12,063, of 1880, which shows a lamp-extinguisher that is inapplicable to a candle in having no ears *g g'* or external means for spreading the jaws apart. In my construction, moreover, the parts *a*, *d d'*, *c c'*, and *f f'* 70 can all be made of one continuous wire, as shown in Fig. 4.

Having thus described the invention and its mode of action, I claim—

1. The apparatus formed of a wire ring, *a*, arms *d d'*, spring branches *c c'*, and horizontal arms *f f'*, all made of one continuous wire, substantially as and for the purpose herein shown and described.

2. The ring *a*, arms *c c'*, horizontal parts *f f'*, ears *g g'*, and eyes *h h'*, combined with the suspenders *t t'* and hook *i*, substantially as herein shown and described.

3. The combination of the ring *a* and arms *c c'* 85 and *f f'* with the ears *g g'*, eyes *h h'*, supports *s s'*, and shade *A*, substantially as herein shown and described.

4. The combination of the ring *a* and arms *c c'* and *f f'* with the ears *g g'* and eyes *h h'*, substantially as and for the purposes herein specified.

LÉON CORDIER PINEL.
